UNITED STATES PATENT OFFICE

ARTHUR K. LAUKEL, OF DETROIT, MICHIGAN

ELECTRODEPOSITED CORE BOX

Original application filed April 10, 1926, Serial No. 101,069. Divided and this application filed December 29, 1928. Serial No. 329,220.

The present application is a division of my co-pending application Serial No. 101,069, filed April 10, 1926, pertaining to a method of making pattern equipment, the working or molding surfaces of which are made by electro deposition. Although the earlier application illustrates the invention as applied to a core box, the invention is of more general scope and is applicable to pattern equipment such as cope and drag plates, match plates and the like. The present invention also is to be understood in this broad sense.

The invention pertains more particularly to a composite element of pattern equipment, exemplified herein by a core box. As already stated, the molding surfaces are formed by electro deposition upon a cast or impression of the object to be reproduced. The impressed surface is then made conductive in any manner known in the art, or as disclosed in my co-pending application Serial No. 108,715, filed May 13, 1926. A metal face plate is now applied to the margin of the conductive surface which is in relief in the case of a core box and depressed or partly depressed and partly in relief in the case of some patterns. The deposit which is plated on the conductive surface obviously adheres to the face plate. The inner surfaces of the face plate and the deposit constitute the working surfaces of the pattern or core box, as the case may be.

A backing member, preferably of metal, is fitted to the back of the deposit and the adjacent face plate in such a manner as to provide an intervening space which is subsequently filled with a filling material such as white metal. The backing member if permanently attached to the face plate by means of screws, in addition to the filling material, and the parts are finally trimmed at the margin, whereby the composite structure is completed.

The invention is fully disclosed by way of example in the following description and in the accompanying drawings in which

Figure 1 is a fragmentary plan view of a mold prepared for plating;

Figure 2 is a transverse section thereof, showing also the deposit thereon;

Figure 3 is a similar section showing in addition the backing plate fitted to the deposit and the face plate;

Figure 4 is a transverse section of the pattern structure removed from the mold and filled; and

Figure 5 is a perspective view of the completed structure.

Reference to these views will now be made by use of like characters which are employed to designate corresponding parts throughout.

In Figures 1, 2 and 3 is illustrated a mold 1 having a formation 2 thereon constituting a counterpart of the object to be reproduced. This mold is formed by pouring a substance such as plaster over the object, which is previously oiled, allowing the substance to set, and then lifting it from the object. The formation 2 is in relief in the case of core boxes, as illustrated, and depressed or partly depressed and partly in relief in the case of some patterns. Throughout the remainder of the specification and in the claims, this formation will be termed "impression", and the applicability of the invention to patterns and core boxes alike will be indicated by identifying these structures generically as an element of pattern equipment.

The mold is treated to resist deterioration by the electrolyte, and the surface of the impression is made conductive, in any manner known in the art or as disclosed in my co-pending application Serial No. 108,715 filed May 13, 1926. A face plate 3 of metal is applied around the margin of the impression in spaced relation thereto and is formed with a bevel edge 4 presented towards the impression. The face plate is secured to the mold 1 by screws 5 passed upwardly through the bottom of the latter. The face plate is now covered by an insulating sheet 6 glued thereto and is suspended in the bath for the plating operation.

After a deposit 7 of sufficient thickness has been formed on the impression 2 and in adherence to the bevel edge 4, the mold is removed from the bath, and the metallic structure thereon is ready for the backing operation.

A cast metal backing member 8 is built with an inner face 9 generally similar to the sur-

100

face of the face plate and deposit. On this inner face are formed ribs 10 which are trimmed or fitted to the metallic structure after removal of the insulator 6 from the face plate. In this fitted relation, as shown in Figure 3, the backing 8 and face plate 6 are drilled and dowelled together by pins 11.

The backing 8 is now removed from the face plate, and the metal surfaces are cleaned with zinc chloride solution to permit adherence of a molten filling metal thereto. The screws 5 are now withdrawn to release the face plate and deposit from the plaster mold. The face plate and deposit are then tinned. The face plate and deposit are laid on a flat surface, and the backing member 8 is superimposed thereon in the position shown in figure 4. The fitted relation obtained in Figure 3 is restored by re-aligning the dowel holes formerly accommodating the pins 11 and the parts are clamped together. The backing member and face plate are now formed with continuous threads into which screws 12 are driven to hold the parts together, and the clamps may now be removed.

The assembled body is heated to approximately the temperature of the filling metal such as white metal, which is now poured into the space between the backing member and face plate, as indicated at 13, either through the sides or through holes drilled in the backing member for this purpose. The dowel holes are thus filled, but are preferably reopened and tapped with continuous threads to receive screws 12. The inner face of the backing member may be notched at 14 to receive the metal for anchorage. Additional screws may now be driven into the parts to hold them together if necessary as desired. All screws are cut or filed off perfectly flush with the exposed side of the face plate as shown in Figure 5. Finally, the backing plate and face plate are trimmed down as far as the outermost rib 15 which becomes a marginal wall enclosing the filling 13.

Although a specific embodiment of the invention has been illustrated and described, it is to be understood that various alterations in the details of construction may be made without departing from the spirit and scope of the invention as indicated by the appended claims.

What I claim is:—

1. The method of making an element of pattern equipment consisting in preparing a mold having an impression or counter part of such element, applying a face plate to said mold and around said impression, preparing the mold for electro deposition, depositing a shell of metal on said impression confined within said face plate, fitting a back plate to said face plate in spaced relation thereto, and filling the space between said plates.

2. The method of making an element of pattern equipment consisting in preparing a

mold having an impression or counter part of such element, applying a face plate to said mold and around said impression, preparing the mold for electro deposition, depositing a shell of metal on said impression confined within said face plate, fitting to the face plate and deposit a back plate having projections thereon, by trimming said projections to conform with said face plate and deposit, and filling the space between said plates.

3. The method of making an element of pattern equipment consisting in preparing a mold having an impression or counter part of such element, applying a face plate to said mold and around said impression, preparing the mold for electro deposition, depositing a shell of metal on said impression confined within said face plate, fitting a back plate to said face plate in spaced relation thereto, and filling the space between said plates with metal.

4. The method of making an element of pattern equipment consisting in preparing a mold having an impression or counter part of such element, applying a face plate to said mold and around said impression, preparing the mold for electro deposition, depositing a shell of metal on said impression confined within said face plate, fitting a back plate to said face plate in spaced relation thereto, removing said face plate and deposit from the mold, removing the back plate from the face plate and deposit, tinning the rough or back surface of said deposit, replacing the back plate on said face plate and deposit in their fitted relation, and filling the space between said back plate and deposit with metal.

5. An element of pattern equipment comprising an electro deposited shell formed on an impression or counter part of such element, a metal face plate surrounding the margin of such shell in adherence thereto, a back plate fitted over said face plate and secured thereto spacedly from the face plate and said shell, and filling material in the space between the backing plate and the face plate and shell.

6. An element of pattern equipment comprising an electro deposited shell formed on an impression or counter part of such element, a metal face plate surrounding the margin of such shell and having an inner beveled edge to which said shell is deposited, a back plate fitted over said face plate and secured thereto spacedly from the face plate and said shell, and filling material in the space between the backing plate and the face plate and shell.

7. An element of pattern equipment comprising an electro deposited shell formed on an impression or counter part of such element, a metal face plate surrounding the margin of such shell in adherence thereto, a back plate fitted over said face plate and secured thereto spacedly from the face plate

and said shell, and metal in the space between the backing plate and the face plate and shell.

8. An element of pattern equipment comprising an electro deposited shell formed on an impression or counter part of such element, a metal face plate surrounding the margin of such shell and having an inner beveled edge to which said shell is deposited, a back plate fitted over said face plate and secured thereto spacedly from the face plate and said shell, and metal in the space between the backing plate and the face plate and shell.

15 In witness whereof I have hereunto set my hand.

ARTHUR K. LAUKEL.
